NAIL FILE

Michael F. Smith, Los Angeles, Calif., assignor of
one-tenth to George L. Schaeffer, Los Angeles,
Calif.

Application May 5, 1941, Serial No. 391,919

2 Claims. (Cl. 132—76.4)

This invention relates to a nail file.

Among the objects of the invention are: To provide for combining a handle and nail file in such a manner that the handle will support the file for use, in a more advantageous manner; to provide for mounting the file upon the handle in a properly exposed condition for use and yet at the same time furnish a secure connection between the file and the handle so that the latter may advantageously be utilized; and to provide for convenient attachment of the file to, and removal thereof from, the handle while still maintaining a securely attached relation of the file to the handle whenever it is desired to use the handle for the file.

More specifically speaking, the invention includes, along with other features, a novel manner of recessing the body portion of a handle to form therein a seat for the attached file.

Other objects, advantages and features of invention will hereinafter appear.

Referring to the accompanying drawing, which illustrates what is at present deemed to be a preferred embodiment of the invention,

Fig. 1 is a side elevation of the device, showing the file in its mounted position upon the comb.

Fig. 2 is a cross section on line 2—2 of Fig. 1.

Fig. 3 is a cross section on line 3—3 of Fig. 1.

Fig. 4 is a longitudinal mid-section of the device.

Referring in detail to the drawing, the comb shown has a body portion 10, and a toothed portion 11 at each end of which is a guard finger or more stocky tooth 12.

Throughout the greater portion of its length the back of the comb body is provided with a main elongated recess 15, the back part of the comb having an intact (as viewed from the side) part 16 at one end of said recess 15, beyond which an auxiliary, smaller recess 17 is provided.

The part 16 is not intact as viewed in cross section, but is provided with a longitudinal groove or slit 19 which extends from end to end thereof. There is also provided, along the bottom of the recess 15, a groove 21 and at the end of said recess opposite to the part 16 a narrow groove 23, the grooves 19 and 23 being continuations of the main groove 21.

The aforesaid grooves are properly dimensioned and positioned to have fitted into them one of the long edge portions of a nail file 25, the groove or slit 23 serving to receive the blunt end of said file while the pointed part 26 of the file projects out into the recess 17.

The blunt end portion of the file is beveled somewhat, as shown in the drawing, and is provided with a series of ratchet-like teeth 27 which are arranged with their short sides directed upwardly, so that when the comb is crowded down into its seated position these teeth bite into the adjacent end portion of the narrow recess or groove 23, thereby preventing this end portion of the file from slipping out of place. The opposite 10 end portion of the file is shown having an angular recess 29, provision thus being made for the formation on the file of a minute tooth 30 which engages a shoulder 31 formed in the comb, to hold in place the pointed end of the file.

15 When the file is attached to the comb both its point portion and its body portion may be advantageously used in cleaning and filing the nails, notwithstanding the fact that the recessed portion 17 of the comb's back guards against the 20 point of the file catching in or tearing the clothing of the user.

The material in the comb's back at each side of the recesses or slits 19 and 23 extends up to the outer edge of the inserted file and grips the latter in such a manner as to prevent it from being given an undesirable rocking or vibrating movement when the comb is utilized as a handle means for the operation of the file. Furthermore, the blunt end portion of the inserted file forms a 30 smooth continuation of the adjacent portion of the comb's back.

The comb, after being equipped with the nail file, may be used as conveniently as before for the usual purpose.

35 The scope of the claimed invention includes using for an elongated handle member other articles than combs, or providing, in place of the comb, a handle member that functions only as such; and in any case the handle member may be 40 molded around the toothed end portions of the file at the time the device is manufactured, rather than the file being forced into its seated position after the handle member has been completely formed.

45 I claim:

1. A handle member of an elongated flat character having a main recess extending along an intermediate portion of its length across the entire width of one of its edge portions, an auxiliary recess extending across said edge portion in a spaced relation to one of the ends of said main recess, thereby providing as seen from the side of the handle, an intact portion between said recesses, and a groove extending from end to end 50 of the bottom of said main recess and through

the mid-width of said intact portion; and a nail file of the elongated flat type fitted within said groove, a portion of the faces of said file being exposed for use by reason of said main recess, said file having a point which projects into said auxiliary recess in a sufficiently exposed position for use and is guarded against contact with the

clothing by the parts of the handle adjacent to said auxiliary recess.

2. The subject matter of claim 1 and, the outer edge portion of said file being in a substantially streamline relation to the parts of the handle adjacent to the ends of said main recess.

MICHAEL F. SMITH.
